UNITED STATES PATENT OFFICE

CASE NUMBER EIGHT, OF BERLIN, GERMANY, ASSIGNEE TO MERGENTHALER LINOTYPE COMPANY, A CORPORATION OF NEW YORK.

WRITING, COMPOSING MACHINE.

卷之三

Specification of Letters Patent.

Application filed June 7, 1913. Serial No. 702,148.

forall x in $\mathcal{M}$ you expect

Be it known that I, David M. McNaughton, a citizen of the United States of America, residing at Indianapolis, Indiana, in the American Empire, have invented new and useful Improvements in Matrix & embossing Machines, of which the following is a specification.

One perceived extension relates to matrix management activities at the Mergers and Acquisitions level and especially to those of the class which has a plurality of management arranged in a column and entitled to being involved in a line of sight meetings with their clients. Another, a short, and perhaps more realistic estimate, is that of the relevant public single asset management, or some of its sub-set, which includes a number of highly diversified firms.

Figure 1 is a side elevation from the right hand, of a revolver equipped with three magazines, the empty parts being in position to complete front and chamber, and the top magazine bars 3 and 4, detail 59 an enlarged view of the front and rear of the column, showing the parts positioned for a quick change. Fig. 2, a plan of the column of magazines and of the means for raising and lowering it. Fig. 3, a section on

the line 5-5 of Fig. 1; Fig. 6, a plan of the improved device for moving the escapement one of and into engagement with the respective escapement levers; Fig. 7, a detail plan of the improved matrix groove in a single magazine bottom plate and escapement part; Fig. 8, a side elevation front view of the right front of a machine equipped with two magazines, illustrating a modification of the detail shown in Figs. 1 to 4; and Fig. 9, a side elevation front view of a machine equipped with two magazines.

This is a copy of the machine framed by the
carriage bracket 3, the magazine frame
4, 5, 6, 7, magazines 5, postbox 6, a metal
compartiment lever 7, the returning spring
8, the magazine rods 9, the respective key
holes 10, the assembler entrance 11, the
disassembler 12, the magazine entrance 13
and the magazine entrance trough 14.

The number of openings may be anything above unity. The present invention prevents their being strained, by supporting the magazine frame 3 at three points, where, points are approximately the angles of an equilateral triangle, two of these points being near the rear and the respective sides of the magazine and the third one intermediate of the said sides and near the front of the magazine as shown in Fig. 4.

The improved means for raising and lowering the magazine frame 3 to effect a quick change consists of three cams 14, 15, 16, 17 in the vertical plane and arranged with reference to each other at the three points just described, the cams 14 and 15 being fast on a shaft 17 turning in bearings in the distributor bracket, and the cam 16 likewise fast on a second shaft 18 turning in bearings in the main frame 1. The three cams are parallel with each other and at right angles with the shafts 17, 18, which are parallel with each other and with the front and rear of the magazines. The magazine frame 3 engages with these cams to

(Figs. 1 and 9) by means of rollers 19 turning in bearings 20 integral with the said frame and depending from it. The particular type of cam is immaterial provided that its operative surface is peripherally long enough, and its radii properly arranged, to deal with as many magazines 4 as there may be in the column. Thus, one rotation of the cams means a quick change from the top magazine in the column to the bottom one.

and vice versa. If there are three magazines in the column, the said surface must be long enough to contain three stopping positions and the lengths of the respective radii of these positions must be according to the distance through which the column has to be moved. Fig. 1 shows the cams proportioned for three positions because there are three magazines 4 in the column. Fig. 9 shows its cams proportioned for two positions because there are two magazines 4 in the respective column. The cams may be either grooved cams embracing the respective magazine frame rollers 19 as shown in Figs. 1 and 5, in which case the outer side of the groove will coöperate with the united weight of the frame 3 and column of magazines 4 in moving them downward and steady their rise, or they may be peripheral ones merely, as those 15^a, 16^a, shown in Figs. 8 and 9. Those parts of the operative surfaces of the cams upon which the rollers 19 bear when the respective magazine is in composing position, consist of hardened portions 21 (Figs. 1 and 5) on the cams to, first, insure exact registration of the said magazine with the assembler entrance 10 and the magazine entrance 12, as well as of its escapement levers 6 with the escapement rods 8, and second, to compensate for wear. Both shafts 17 and 18 are turned by a winch handle 22 fast on the outer end of a front to rear shaft 23 turning in bearings 24 on the machine frame 1 and distributor bracket 2 on the right hand side of the machine, and miter gears 25, the latter being so arranged that the two shafts 17 and 18 shall be turned in the same direction to allow of all the cams thereon being replicas of each other. In all respects, the said gears 25 being so proportioned that one turn of the handle 22 is equivalent to only a quick change from one magazine to the one next to it.

26 is a bar fast on the machine frame 1 on each side of the magazine column and so positioned thereon as to hold a rear edge parallel with the direction in which the column is moved, and 27, a roller pivoted on each side of the magazine frame 3 so as to engage with the said edge for the double purpose of guiding the column and preventing it slipping to the front. Fig. 9 shows a substitute for the bar 26 and roller 27, consisting of a stud 27^a on each side of the magazine frame 3 engaging in a slot 26^a in each side of the distributor bracket 2.

The combination of cams and rollers, as supports and quick changing means, may be replaced by any suitable mechanical equivalent such as a set of three levers, three bell crank levers, or three screws mounted on the machine frame 1.

The improved means for balancing the weight of the magazine frame 3 and magazine column, consists of a bar 28 having its

top end loosely connected to the center of the magazine frame 3 and its bottom end working in a guide 29 fast on the machine frame; a spring or springs 30 fast by one end to the machine frame 1 and connected by the other end to the said bar 28 in such a way that it or they are constantly balancing the said weight, thereby preventing it being felt by the operator as he makes a quick change. The connection 31 between the spring factor and the bar 28 is of such a type that the strength of that factor can be regulated according to variations in the weight of the magazine column caused by substitution of heavier or lighter magazines for those in it. This spring factor may be replaced by any mechanical equivalent consisting of either springs or weights.

To further insure the above mentioned registration of the magazine to be composed from with the assembler entrance 10 and the magazine entrance 12, the invention provides a locking disk 32 fast on the shaft 23 and having one notch 33 in its periphery; a hand lever 34 fulcrumed at 35 on the machine frame so as to be easily disengaged from the said notch by the operator, and engaged in it by a spring 35^a, and also carrying a stud 36 which is engaged by the top or bottom notch 37 or 38 in a locking arm 39 pivoted on some stationary part of the machine, *e. g.*, the assembler entrance 10. This arm 39 is kept so engaged by a suitable spring such as 40. The arrangement of these parts is such that when the lever 34 is engaged in the notch 33, one of the notches 37 or 38—the top one according to the construction illustrated—engages the stud 36 and when the said lever 34 is disengaged from the said notch 33, the other notch automatically engages the said stud.

For the reason that a machine of the class stated, has only a single assembler entrance 10 and a single distributor 11 with its single magazine entrance 12, a quick change can be effected only when the matrices that have been assembled, have been returned into the magazine in composing position by the distributor 11, during which they slide through the magazine entrance 12 and may stick before they are wholly within the said magazine; and also when no matrices are projecting from the delivery mouth of that magazine.

The present invention prevents a quick change under either of the above circumstances by the following means: First, as to the distributor. 41—Figs. 1 and 3—is a matrix detector fast upon a bell crank lever 42 pivoted at 43 upon brackets 44 projecting rearwardly from the distributor 11 and connected to the above described lever 34, by any means capable of making that motion of the said lever which disengages it from the disk 32, move the detector 41 into the path

of the matrices as they pass along the distributor 11. The constructional details of the said means are not illustrated because they are of no importance. It is only their function that is part of the invention and these details may be varied to any extent so long as the function is retained. The presence of the said means is indicated by the broken line 45. The action of it is such that the detector 41 can move into the said matrix path and the lever 34 disengage from the disk 32 only after all the matrices have dropped from the distributor 11 into the magazine entrance 12; so that so long as there is even one matrix hanging from the said distributor, the lever 34 cannot be disengaged from the disk 32, whereby a quick change is impossible. The detector 41 is held out of the said matrix path by the engagement of the lever 34 with the disk 32. Secondly, as to the magazine entrance 12 and the respective entrance mouth of the magazine in composing position: 46 is a second matrix-detector. It is fast to the rear end of a bell crank lever 47 on each side of the magazine column and fulcrumed at 48 on the main frame near the rear of the column and connected by its opposite end to the means 45 above mentioned. The position, dimensions, and action of the detector 46 are such that when the lever 34 is engaged with the disk 32, it is held by the means 45 and its lever 47 above the entrance mouths of all the magazines in the column; and that when the said lever 34 is fully disengaged from the disk 32, it is moved downward far enough to cover the said magazine entrance mouth. Thirdly, as to the delivery mouth of the magazine in composing position: 48—Figs. 1 and 2—is a third matrix-detector. It is fast to the top end of a bell crank lever 50 fulcrumed at 51 on each side of the upper entrance 10 and connected by its opposite end to the said means 45; the position, dimensions, and action of this detector 49 being such that when the lever 34 is engaged with the disk 32, it is held by the means 45 and its levers 50 to the front of the plane of the delivery mouths of the magazines in the column, and that when the lever 34 is fully disengaged from the disk 32, it is moved downward exactly in front of the delivery mouth of the magazine in composing position, but if even one matrix is, at the time, protruding from either the entrance mouth or the delivery mouth of the last mentioned magazine, the lever 34 cannot be disengaged from the disk 32, so that no quick change can be effected. Fig. 8 shows a means by which a quick change can be effected in spite of the protrusion of a matrix (or more than one) from the entrance mouth of a magazine. These means consist of a cam disk 52 fast on the shaft 23 already described and hav- ing a notch 53 in its front face; a roller 54 on the bottom end of a lever 55 fulcrumed at its middle at 56 on the machine frame 1; and a push rod 57 slotted to slide on a guiding pin 58 on the distributor bracket 2 and having its front end pivotally connected to the top end of the lever 55 while its opposite end is in permanent contact with the magazine entrance 12, the arrangement being that so long as the magazine entrance 12 is closed up to the magazine in composing position, the roller 54 is engaged in the notch 53, as shown by the full lines, but as soon as the operator turns the handle 22, the rise on the cam disk 52, rocks the said magazine entrance open, so that its front face is clear of any matrix 5 which may then be protruding from the entrance mouth of the said magazine, as shown by the dotted lines, whereby the quick change is not interfered with. When it has been effected the magazine entrance 12 is rocked into its operative position either by hand or a returning spring (not shown).

Referring to the escapement rods 8, each one gets at its respective escapement lever 6 through a lever 59 centrally fulcrumed on the bottom plate of the respective magazine, the front ends of these levers being flush with the delivery mouths of the magazines 4. The well-known spring 7 which rocks the tail of a lever 6 down, keeps the front end of a lever 59 down upon the top of its rod 8, which top is bent to the rear far enough to engage under the said end of a lever 59 when the rod itself is in operative position. 61 is the improved device for embracing all the rods 8 and moving them out of and into engagement with the levers 59. As compared with the devices hitherto known for this purpose, it consists of a notch 62 in the rear edge of each rod 8; a frame 63 fast to the lever 34; a rod 64 extending from one side of the frame to the other and lying in the notches 62 which are aligned to receive it; and a member 65 in front of the rods 8 and in constant engagement with them. This device has the advantage over the previous ones, that there are no rearward projections from either it, or from the rods 8 after the latter have been disengaged from the levers 59, to foul the delivery mouths of the magazines as the column of them is being moved up or down for a quick change.

Fig. 9 illustrates improved means for preventing a matrix of a wrong font getting into the well-known distributor box 66. This box stands in front of the distributor 11 (speaking in terms of the course followed by the matrices through the machine) and each matrix must in turn enter it and pass through it before it has a chance of getting onto the said distributor. The said means are particularly applicable to a ma-

chine of the class stated, because they will prevent cartridges on their way to the distributor, getting onto the latter, in the event of a quick change having moved their proper magazine out of the chambering position. They comprise a rod 67, pivoted transversely through the distributor box 66 near its center and just below the plane of the magazine feed; a pin 68 is upon the top of the rod 67, and to the pin 68, together with the rod, the well known wrong foot selector is fastened; a lever 69 is pivoted at 70 on the distributor bracket 71, a lever 72 being connected to the operative end of the upper arm of the lever 72 fast on the shaft 73; the lever 72 being a series of pins fast to, pivoting radially from the lever 72 in the vertical plane that contains the lower arm of the lever 72, and symmetrically arranged about the said lower arm 72 and a spring 74 between the midpoint front end of the rod 67 and the distributor box 66, capable of keeping the said lower arm in touch with the series of pins 72. There are no cartridge pins 75 in a series as there are magazines in a column, and they are of different lengths, the radial length of each pin and its angular position on its shaft 73 being such that when a quick change is desired, one of them will be lever 69, or allowing the spring 74 to rock it, for example, to position the pin 75 in the line of the well known four notch 68a in the foot of the cartridges belonging to the magazine then being quick changed into the chambering position. The function of the spring 74 is to yield when ever a pin 75 would drive the selector to the rear when the pin 75 is engaged in the notch 68a.

It frequently happens with a number of magazines that when the magazine entrance 12 is rocked down to the position of a loaded magazine, the magazine slips in the slot entrance, will trip out the magazine, then under the rear of the magazine position 15 and will be carried through the slot 14 exposed by the rocking down of the entrance 12. To prevent such slipping, the present invention provides (Fig. 1) a flat closing plate 78 fast on the steel fence wall and which is so dimensioned and positioned that the entrance ports of all the magazines 10 are true under the slot in rock-down position that are closed by it. The nail-like catching 55 trough 13 is fast to the bottom edge of the plate 78 to receive the magazines from the rocked down magazine entrance 12.

According to the present invention, the holes 18 -Fig. 7- in the bottom plate of a magazine and the escapement pawls 79 to 82 working through them are circular in cross section, and their diameter is less than the width of a matrix groove 80, whereby there is less obstruction to the motion of the matrices than when the pawls are rectangular.

bar and the holes are also rectangular and extend across the groove for its full width.

is a matrix composing machine of the 70 class series, the combination with its movable column of magazines and the supporting frame for said column, of three supports arranged under the supporting frame approximately at the angles of an equilateral triangle.

is also a motor comprising machine of the
kind, and the combination with its main-
taining frame or rigid exterior, of three oppo-
site, arranged under the supporting truss
appropriately at the angles of an equi-
lateral triangle, having one side parallel with
the members of the magazines.

3. In a main composing machine of the 50 class stated, the combination with its movable carriage of magazines and the supporting frame by side column, of three supports arranged under the supporting frame approximately at the angles of an equilateral triangle, having one side parallel with and near in the entrance mouth of the magazines and the subtending angle near to their vertical mouth.

1. As a matrix consisting readily of the 48 class marked the combination with its movable column of magazines, of a set of supporting arms mounted independently of the said column and arranged under it approximately at the angles of an equilateral triangle, and means for turning all the arms to effect a quick change.

3. In a neutrino composing machine of the class set out, the combination with its new objective of magazines, of a set of supporting arms mounted independently of the said column and arranged under it approximately at the angles of an equilateral triangle, and means for turning all the said arms simultaneously to effect a quick change.

In a matrix composing machine of the class stated, the combination with its movable column of magazines, of a set of supporting cams, each one a replica of the other, mounted independently of the said column and arranged under it at both its front and rear, and means for turning all the cams to effect a quick change.

7. In a matrix composing machine of the class described, the combination of assembling devices, a plurality of magazines movable as a whole to bring any selected one into operative relation to the assembling devices, and a system of rotary supporting arms mounted to turn about horizontal transverse axes for moving the magazines when desired. 120 125

3. In a matrix composing machine of the

class stated, the combination with its movable column of magazines, of means for raising and lowering it to effect a quick change, and a spring device acting independently of said means to balance the weight of the said column, consisting of a bar loosely connected with the central point of the bottom face of the column and depending therefrom, and a spring connecting the opposite end of the said bar to a fixed point above it and independent of it and of the column.

9. In a matrix composing machine of the class described, the combination with its movable column of magazines, a system of rotary means for raising and lowering the column to effect a quick change, and an operating shaft for rotating the column, the said means being so constructed that one complete rotation of the operating shaft will effect a quick change from each magazine to the next one in the column, together with means for locking the shaft against rotation.

10. In a matrix composing machine of the class stated, the combination with its movable column of magazines, of rotating means for raising and lowering it to effect a quick change; and a locking device to lock the said means after each rotation, consisting of a rotating disk, a nut in it, and an independently fulcrumed lever capable of engaging in the said nut.

11. In a matrix composing machine of the class stated, the combination with its movable column of magazines, of means for raising and lowering it to effect a quick change, and locking and rotating devices for actuating the said means, the said means being so constructed that one rotation of the devices will effect a quick change from each magazine to the next one in the column.

12. In a matrix composing machine of the class stated, the combination with its movable column of magazines, means for raising and lowering it to effect a quick change and a locking device capable of locking the said means after each quick change, of a matrix detector capable of slipping over the entrance mouth of all the magazines and means operatively connecting it to the said locking device so as to prevent it being unlocked when the detector detects a matrix protruding from an entrance mouth.

13. In a matrix composing machine of the class stated, the combination with its movable column of magazines, means for raising and lowering it to effect a quick change and a locking device capable of locking the said means after quick change, of a matrix detector consisting of a plate capable of closing the entrance mouths of the magazines, and quick levers fulcrumed independently of the said column and carrying the said plate, and means operatively connecting the said levers to the locking device so as to prevent it being unlocked whenever the said

detector detects a matrix protruding from an entrance mouth.

14. In a matrix composing machine of the class stated, the combination with its movable column of magazines, means for raising and lowering it to effect a quick change, a locking device capable of locking the said means after each quick change, of a matrix detector capable of detecting an undistributed matrix sent to the distributor; a matrix detector capable of detecting a matrix protruding from an entrance mouth of a magazine; and means operatively connecting both detectors to the said locking device to prevent it being unlocked whenever so either detector detects a matrix.

15. In a matrix composing machine of the class stated, the combination with its movable column of magazines, means for raising and lowering it to effect a quick change and a locking device capable of locking the said means after each quick change, of a matrix detector capable of detecting a matrix protruding from the entrance mouth of a magazine; and means operatively connecting both detectors to the said locking device to prevent it being unlocked whenever either detector detects a matrix protruding.

16. In a matrix composing machine of the class stated, the combination with its movable column of magazines, means for raising and lowering it to effect a quick change and a locking device capable of locking the said means after each quick change, of a matrix detector capable of detecting a matrix protruding from the entrance mouth of a magazine; and means operatively connecting both detectors to the said locking device to prevent it being unlocked whenever either detector detects a matrix protruding.

17. In a matrix composing machine of the class stated, the combination with its movable column of magazines, means for raising and lowering it to effect a quick change and a locking device capable of locking the said means after each quick change, of a matrix detector consisting of a plate capable of closing the entrance mouths of the magazines, and quick levers fulcrumed independently of the said column and carrying the said plate, and means operatively connecting the said levers to the locking device to prevent it being unlocked whenever the said

detector detects a matrix protruding from an entrance mouth of a magazine; and rotary means for raising and lowering it to effect a quick change and a magazine lifter capable of being moved out of operative relation with said magazine and direct connection thereto to the raising and lowering means and operated by the latter.

18. In a matrix composing machine of the class stated, the combination with its movable column of magazines, means for raising

- tionship with the said column, of means actuated by the said rotary means to push the said magazine entrance out of operative relationship with the said column and consisting of a cam disk turning with the said rotary means; a notch in the said disk; a lever independently fulcrumed and engaging by one end alternately with the face of the disk and in the notch; a push rod guided in stationary guides independent of the column, pivotally connected by one end with the other end of the said lever and having its opposite end in touch with the magazine entrance.
19. In a matrix composing machine of the class stated, the combination with its movable column of magazines, escapement levers and escapement rods, of a series of aligned notches in the rear edge of the latter; a frame in front of the said rods carrying a rod lying in the said notches and a plate in touch with the front edges of the escapement rods; and means for reciprocating the said frame to put the escapement rods out of and into operative relationship with the escapement levers.
20. In a matrix composing machine of the class stated, the combination with its movable column of magazines, means for raising and lowering it to effect a quick change, and its wrong font rejector, of connections therefrom to the said raising and lowering means capable of making the said rejector assume an operative position corresponding with the magazine that has been quick changed into operative position.
21. In a matrix composing machine of the class stated, the combination with its movable column of magazines, rotary means for raising and lowering it to effect a quick change, and its wrong font rejector, of connections therefrom to the said rotary means capable of making the said rejector assume an operative position corresponding with the magazine that has been quick changed into composing position.
22. In a matrix composing machine of the class stated, the combination with its movable column of magazines, rotary means for raising and lowering it to effect a quick change, and its wrong font rejector, of a set of pins radially arranged about one of the axes of said rotary means, there being as many pins as there are magazines in the said column, each one of a different length according to distance which the said rejector must be moved by a quick change to pass the matrices belonging to the magazine then in composing position; and means operatively connecting the said series of pins with the said rejector to move the latter into the position corresponding with the magazine that has been quick changed into composing position.
23. In a matrix composing machine of the
- class stated, the combination with its movable column of magazines, rotary means for raising and lowering it to effect a quick change, and its wrong font rejector, of a set of pins radially arranged about one of the axes said rotary means, there being as many pins as there are magazines in the said column, each one of a different length according to the distance which the said rejector must be moved by a quick change to pass the matrices belonging to the magazine that has been quick changed into composing position; and means consisting of a lever and a spring operatively connecting the said series of pins with the rejector, to move the latter into the required position.
24. In a matrix composing machine of the class stated, the combination with its movable column of magazines, rotary means for raising and lowering it to effect a quick change, and its wrong font rejector, of automatic means controlled by the said rotary means capable of making the rejector assume an operative position corresponding with the magazine that has been quick changed into operative position; and means for permitting the rejector to yield when it is engaged with a matrix.
25. In a matrix composing machine of the class stated, the combination with its movable column of magazines, rotary means for raising and lowering it to effect a quick change, and its wrong font rejector; of a set of pins radially arranged about one of the axes of the rotary means, there being as many pins as there are magazines in the column, each one of a different length according to the distance which the rejector must be moved by a quick change to pass the matrices belonging to the magazine that has been quick changed into composing position; means consisting of a lever and a spring operatively connecting the said series of pins with the rejector, to move the latter into the required position; and means for permitting the rejector to yield when it is engaged with a matrix.
26. In a typographical machine, the combination of a plurality of magazines, means for raising and lowering the magazines to bring any selected one thereof into operative position, a magazine entrance to cooperate with the selected magazine, and devices operated directly by said means for moving the entrance out of operative relationship with said magazine.
27. In a typographical composing machine, the combination of a plurality of shiftable magazines, a laterally movable font distinguisher, and mechanism for automatically moving the distinguisher laterally as the magazines are shifted.
28. In a typographical composing machine, the combination of a plurality of shiftable magazines, the laterally adjustable

font distinguisher, and a lever actuated by the shifting of the magazines to adjust the font distinguisher.

29. In a typographical machine, the combination of a plurality of magazines, a laterally adjustable font distinguisher and means for automatically adjusting the font distinguisher laterally to correspond to the magazine in operation, the said means comprising devices of variant form; one for each magazine to control the extent of adjustment.

30. In a typographical machine, the combination of a plurality of movable magazines, an adjustable font distinguisher, and a rotary device controlled by the movement of the magazines and provided with projecting pins of different extent to adjust the font distinguisher to correspond to the magazine in use.

31. In a typographical machine, the combination of a laterally movable font distinguisher, an operating part therefor, and a yielding connection between the two to permit the movement of the operating part when the font distinguisher is arrested by a matrix in engagement therewith.

32. In a typographical machine, the combination of a laterally movable font distinguisher spring-pressed in one direction and operating mechanism for moving it in the opposite direction, the said mechanism being adapted to yield when the movement of the font distinguisher is prevented by its engagement with a matrix.

33. In a typographical machine, the combination of a laterally movable font distinguisher, and an operating lever therefor, the said lever being provided with a yielding part to connect it with the font distinguisher to allow the lever to give in the event that the movement of the font distinguisher is arrested by its engagement with a matrix.

34. In a typographical machine, the combination of a shiftable magazine for the matrices, and independent locking means controlled by the matrices for preventing the shifting thereof when a matrix is protruding from its upper or receiving end.

35. In a typographical machine, the combination of a shiftable magazine for the matrices, movable locking means for preventing its shifting, and a matrix feeler connected to the locking means and serving to prevent their release when a matrix is protruding from the upper or receiving end of the magazine.

36. In a typographical machine, the combination of a magazine, a magazine entrance to deliver the matrices thereto, and means movable at will between the magazine and entrance to detect the presence of a matrix lodged therebetween.

37. In a typographical machine, the combination of a magazine, a magazine entrance

to deliver the matrices thereto, an assembler entrance to receive the matrices therefrom, and two connected matrix feelers, one movable between the magazine and the magazine entrance, and the other between the magazine and the assembler entrance; whereby the operator may determine at will whether a matrix is protruding from either end of the magazine.

38. In a typographical machine, the combination of a shiftable magazine for the matrices, movable locking means to prevent its shifting, and matrix feelers located at the opposite ends of the magazine and connected to the locking means; whereby the shifting of the magazine will be prevented when a matrix is protruding from either of its ends.

39. In a typographical machine, the combination of a magazine for the matrices, distributing mechanism, matrix feelers to detect the presence of matrices in the distributing mechanism or their protrusion from either end of the magazine, and connections between the several feelers whereby they may be operated simultaneously.

40. In a typographical machine, the combination of a shiftable magazine for the matrices, distributing mechanism therefor, and locking means to prevent the shifting of the magazine, together with matrix feelers connected to the locking means and acting to detect the presence of matrices in the distributing mechanism or their protrusion from either end of the magazine.

41. In a typographical machine, the combination of a shiftable magazine provided with escapements, escapement actuating devices, and means to prevent independently of the escapements and their actuating devices the shifting of the magazine while they are connected to each other.

42. In a typographical machine, the combination of a shiftable magazine provided with escapements, escapement actuating devices, means for shifting the magazine, and independent locking mechanism for preventing the operation of said shifting means while the actuating devices are engaged with the escapements.

43. In a typographical machine, the combination of a plurality of shiftable magazines each provided with escapements, escapement actuating devices movable into and out of operative relation to the escapements of one or another of the magazines, and independent locking means for preventing the shifting of the magazines until the escapement actuating devices have been moved from their operative position.

44. In a typographical machine, the combination of a plurality of shiftable magazines each provided with escapements, escapement actuating devices movable into and out of operative relation to the escape-

ments of one or another of the magazines, movable locking means for the magazines, and connecting whereby the release of the locking means will automatically effect the movement of the escapement activation devices to their inoperative position.

45. In a typographical machine, the combination of a magazine for the matrices provided with escapements, escapement releasing devices movable from their operative position, a matrix detector movable across the path of travel of the matrices, and movable locking means for the magazine together with connections between said movable parts whereby they will be operated simultaneously.

46. In a typographical machine, the combination of a magazine for the matrices, distributing mechanism, means to determine whether a matrix is protruding from the upper or receiving end of the magazine, means to determine whether a matrix is present in the distributing mechanism, and connection between the two said means whereby they may be operated simultaneously at will.

47. In a typographical machine, the combination of a slidable magazine for the matrices, distributing mechanism, movable locking means to prevent the shifting of the magazines, and two matrix feelers each connected to the locking means, one adapted to detect the presence of matrices in the distributing mechanism and the other adapted to detect their protrusion from the upper end of the magazine.

48. In a typographical machine, the combination of a plurality of magazines slidable to bring one or another thereof into operative position, a magazine means to cooperate with the operative magazine, and manually operable devices acting directly to

move the entrance out of operative relation to the said magazine when the magazines are shifted.

49. In a typographical machine, the combination of a magazine, a magazine entrance to cooperate therewith, and means for moving the entrance out of operative relation to the magazine at will, the said means comprising an operating handle located at the front of the machine, and connections therefrom directly to the magazine-entrance.

50. In a typographical machine, the combination of a laterally movable font dis- 55 tinguisher, operating mechanism therefor and a spring through which the operating mechanism acts; whereby the said mechanism is adapted to yield when the movement of the font dis- 60 tinguisher is unduly resisted or arrested.

51. In a typographical machine, the combination of a movable font distinguisher, operating mechanism therefor, and a spring 65 through which the operating mechanism is adapted to yield relatively to the font dis- 70 tinguisher when movement of the latter is unduly resisted or arrested.

52. In a typographical machine, the combination of a movable font distinguisher a spring for moving it in one direction, and operating mechanism for moving it in the opposite direction, said mechanism being adapted to yield when the movement of the 75 font distinguisher is unduly resisted or arrested.

In witness whereof I have hereunto set my hand in the presence of two witnesses.

CARL MUEHLEISEN.

Witnesses:

Woltemar Hauff,
Henry Hassek.
